(57) **CLAIM**

The ornamental design for fishing reel, as shown and described.

DESCRIPTION

FIG. 1 is a perspective view of the back cone of a fishing reel embodying the design of the present invention.

FIG. 2 is a left side elevational view of the fishing reel illustrated in FIG. 1.

FIG. 3 is a right side elevational view of the fishing reel illustrated in FIG. 1.

FIG. 4 is a front elevational view of a fishing reel incorporating the back cone illustrated in FIG. 1.

FIG. 5 is a rear elevational view of the fishing reel illustrated in FIG. 1.

FIG. 6 is a top plan view of the fishing reel illustrated in FIG. 1; and,

FIG. 7 is a bottom view of the fishing reel illustrated in FIG. 1.

The environmental structure shown in broken lines forms no part of the claimed design.
